Primary Examiner—Terry A. Wallace(74) *Attorney, Agent, or Firm*—Jason H. Foster; Kremblas, Foster, Phillips & Pollick(57) **CLAIM**

The ornamental design for a beverage can cooler, as shown and described.

DESCRIPTION

FIG. 1 is a perspective view of a beverage can cooler showing my new design, the can is shown in broken lines for illustrative purposes only and forms no part of the claimed design;

FIG. 2 is a top view thereof.

FIG. 3 is a bottom view thereof; and,

FIG. 4 is a side view thereof. All other sides thereof are substantially identical.
